MACHINE FOR MOLDING CONCRETE BLOCKS

John R. Sims, El Monte, Calif., assignor of one-half to Marvin Say, Manhattan Beach, Calif.

Application July 20, 1946, Serial No. 685,272

9 Claims. (Cl. 25—41)

1

This invention relates to an apparatus for molding plastic products and pertains more particularly to a mold for forming concrete bricks. A general object of the invention is to provide an improved mold that expedites casting and at the same time produces a cast with smoother surfaces and of a higher density.

A primary feature of the invention is the provision of vibratory sides for the mold that are free to vibrate laterally as the mold is vibrated vertically during the casting operation, producing a cast of finer quality. The laterally vibrating sides of the mold brings the finer particles of the cast to its side surfaces, while the vertical vibrations of the mold brings moisture and fine particles to its top and bottom surfaces, assuring smoother surfaces all over and a casting of a higher density throughout. Particularly important is the capacity of the mold sides, because of their vibratory condition, to free themselves from and prevent adherence of the cast.

Another object of the invention is to provide a mold for forming hollow brick, wherein the mold body and its core are connected together in a unit with limited relative parting movement, allowing the core to be first stripped from the cast, followed by stripping of the mold body. In this manner the core and the mold body may be removed from the cast as a unit and in one operation.

Another feature of the apparatus is the provision of a guard or flange overlying the upper portion of the mold, that is connected with the mold carrying structure for engaging the core assembly to retain the core in position and in turn locate and secure the mold on its pallet. The result is a complete molding unit that can be readily handled before and after the casting operation.

Other features and objects as well as those above mentioned, will be more readily understood from a detailed description of a typical embodiment of the invention, reference being had to the accompanying drawings, in which:

Fig. 1 is a central longitudinal sectional view through a molding apparatus embodying the invention;

Fig. 2 is an enlarged transverse vertical sectional view taken on line 2—2 of Fig. 1;

Fig. 3 is a plan view of the mold proper;

Fig. 4 is a fragmentary enlarger perspective view of a corner of the mold illustrating the free vibratory side portions of the mold; and

Fig. 5 is a fragmentary broken sectional view showing a variational form of the invention.

This invention relates to a mold apparatus and method of molding a concrete block or the like having a smooth surface and a free vibratory side portion. The mold is supported on a vibratory table which is supported on a frame having a lower deck and an upper deck. The mold is supported on the lower deck and the vibratory table is supported on the upper deck. The vibratory table is supported on the lower deck through spaced compression springs located at its opposite sides. The vibratory means includes an electric motor carried by a suitable bracket on the lower deck, the motor shaft having a crank arm carrying a crank pin for connection with a pull cord attached to the underside of the vibratory table, preferably at its center of mass as illustrated.

Downward rotation of the crank arm by the motor shaft produces downward movement of the vibratory table through the pull cord against the resistance of the springs, and upward rotation of the arm allows the springs to return the table to its raised position, producing vertical vibrations in the mold unit. The mold unit includes generally a mold proper supported by a removable pallet and releasably connected therewith by a resilient clamp means. Typically the mold is a double cavity mold having side walls or flanges joined at their ends by end walls or flanges and a central wall dividing the mold into two cavities. The side flanges, the end flanges, and the dividing wall, are so constructed as to be capable of independent vibration. The adjoining side and end flanges are connected together by welding located at their lower portions to leave free upper portions for independent vibration. The dividing wall is connected with the end walls by welding at its lower engaging portion to have a free upper portion for independent vibration.

The mold is designed to form the standard hollow concrete bricks for building structures, and is provided with cores for the cavities. The core includes a pair of spaced rectangular hollow block sections extending vertically through the mold, and having slightly downwardly converging side walls to facilitate removal from the cast. Connecting web is attached to opposing sides of the spaced core blocks at their upper ends. The web is semi-circular in cross-section to form a semi-circular groove in the upper surface of the cast. Similarly shaped projections extend

from the top of the core sections to engage the connecting web. The mold is supported on a vibratory table which is supported on a frame having a lower deck and an upper deck. The mold is supported on the lower deck and the vibratory table is supported on the upper deck. The vibratory table is supported on the lower deck through spaced compression springs located at its opposite sides. The vibratory means includes an electric motor carried by a suitable bracket on the lower deck, the motor shaft having a crank arm carrying a crank pin for connection with a pull cord attached to the underside of the vibratory table, preferably at its center of mass as illustrated.

from the opposite sides of the blocks 38 and in the same plane as the web 39 to form continuations of the groove in the upper surface of the cast. The projections 40 and 41 extend to points outside of the mold 24 for purposes to be later described.

The core 37 for the cavity 32 is provided with a pair of spaced core blocks 42 similar to the blocks 38 described above. Web 43 connected with the opposing sides of the blocks 42 at their upper end, is semi-circular in cross-section and in the same plane as the web 39. Web 43 is provided with a splitting plate 44 extending from the top to the bottom of the mold and centrally in the cavity 32, has the same transverse area as the core blocks 42. The plate 44 provides a weakened portion in the cast brick to facilitate splitting into two sections where a half brick is required. The core 37 is provided with projections 45 and 46, similar to the projections 40 and 41 of the core 36, extending outwardly from the opposite sides of the blocks 42 at their upper ends and in the same plane as the web 43 to form a continuous groove across the top face of the cast. The projections 45 and 46 extend to points outside of the mold 24 for purposes to be later described. A downwardly extending leg 45a, of semi-circular cross-section, carried by the projection 45 is located adjacent the end wall 29 of the mold to form a vertical groove in the end of the brick.

The cores 36 and 37 are attached to the mold 24 by slack connection 47 including L-shaped brackets 48 connected with the undersides of the several projections 40, 41, 45 and 46 and carrying vertical bearing tubes 49. Brackets 50 connected with the opposite end walls 29 and 30 at their point of welding 34, carry vertically extending spaced pins 51 to be slidably received in the tubes 49 for guiding the cores in their vertical movement relative to the mold 24. Heads 52 are provided at the upper ends of the pins 51 for limiting the upward movement of the cores 36 and 37 relative to the mold 24. A bar or handle 53 connects the adjacent tubes 49 at the opposite ends of the cores to cause the cores to move in unison.

Resilient clamp means 26 associated with the table 16, locates and retains the mold 24 and its cores in position on the removable pallet 25. Table 16 is a substantially rectangular plate and pivotally carries a clamp 26 through hinge connection 54 at one side of the table. The hinge connection 54 is preferably adjustable vertically relative to the table 16 by spaced lock nuts 54a, see Fig. 1, to compensate for variations in thickness of the pallets 25. The clamp may be in the form of an angle iron frame 55 surrounding the upper marginal portion of the mold 24 and engaging the outer end of the projections 40, 41, 45 and 46 of the cores 36 and 37 to locate and retain the cores in position. The projections are each provided with a recess 56 for receiving the top flange of the clamping frame 55 so that the latter has its upper surface in the same plane as the top surface of the projections and the core, as clearly illustrated in Fig. 2.

A resilient attachment in the form of a spring 57 connected between the clamp frame 55 and the table 16, releasably holds the clamp frame 55 in a position where its upper surface and the upper surfaces of the cores are flush with the upper edge of the mold 24, and the several semi-circular projections 40, 41, 45 and 46 are received in notches 58 in the upper edges of the end

walls 29 and 30. Springs 59 surrounding the stems 51 between the underside of the tubes 49 and the upper surface of the brackets 50, transmit downward force from the clamp 26 to the mold 24 for retaining the mold on the pallet 25. The frame 55 surrounds the upper edge of the mold 24 with suitable clearance to allow free vibration of the side and end walls of the mold 24.

Means in addition to clamp 26 may be included to assure proper positioning of the mold 24 on the removable pallet 25, and the location of the pallet on the vibratory table 16. For example, pins 70 may locate the mold on the removable pallet, and pins 71 position the pallet on the table. When the mold and the pallet are centered by the pins 70 and 71, the clamp 26 may be freely pivoted into clamping position with the unit in proper register with the material hopper 161.

The form of molding unit 62 illustrated in Fig. 5 of the drawings includes a removable pallet 65 for supporting the mold 24 and a resilient clamp 66, identical to the clamp 26 described above, directly attached to the removable pallet 65 instead of the vibratory table 16. A hinge connection 63 at one side of the unit pivotally attaches the clamp frame 68 to the pallet 65 and a releasable resilient latch 67 at the other side of the unit retains the mold on the pallet to form a complete assembly or unit that may be readily handled during the molding operations.

In operation, the mold 24 and its cores 36 and 37 are connected together by the slack connection 47 to form a unit. The clamping means 26 carried by the table 16 is adapted to receive the mold 24 and its cores and locate the mold on the pallet 25, as illustrated in Figs. 1 and 2.

The mold is positioned on the pallet 25, frame 55 pivoted downward to bring the cores into position in their mold cavity, and the latch 57 engaged to yieldingly hold clamp 26 and bring the upper surfaces of the frame 55, cores 36 and 37 flush with the upper edge of the mold. The unit when in position on the vibratory table 16 has its upper surface in the same plane as the upper surface of the deck 15. The raw material hopper 161 is reciprocably carried by the frame 61 in a suitable manner to permit its being pulled forward by handle 60 to the dotted line position illustrated in Fig. 1, where its open bottom is in communication with the mold to fill the same and returned to the full line position of Fig. 1, at the same time wiping off the cast where it is flush with the upper edge of the mold. Energization of the motor 18 causes vertical vibration of the table 16 and the molding unit 12 supported thereon. The sides 27, 28, 29, 30 and the central dividing wall 33 of the mold are free to vibrate laterally to bring the moisture and the finer particles to all surfaces of the cast and in turn produce a smooth high density surface freely and completely separable from the mold.

Upon completion of the cast, the latch 57 is released to allow the clamp means 26 to be pivoted back to facilitate removal of mold 24 and pallet 25 from the table 16. Lifting of the handles 53 by the operator will first strip cores 36 and 37 from the cast, followed by stripping of the mold from the cast due to slack connection 47 between the cores and the mold. The mold and its core are stripped from the cast simultaneously in one operation and are retained in a unit by the slack

connection 47 to be ready for a subsequent molding operation.

The bottom edge of the material hopper 161 and the top surface of the removable pallet may be given any configuration other than the straight line shown, to conform to the desired shape of the product being molded or effect to be produced on its top or bottom surfaces.

I claim:

1. A molding apparatus of the character described including, a mold, a core for said mold having a projection extending outside of said mold, a bottom support for said mold, a guard pivotally connected with said support and surrounding the upper portion of said mold for engaging said projection to locate and retain said mold and core on said support and means for releasably connecting said guard with said support.

2. A molding unit of the character described comprising a mold having vibratory sides, a bottom support for said mold, a guard connected with said support and surrounding the upper portion of said mold with clearance to permit vibration of said sides, and means engageable by said guard to locate and retain said mold on said support.

3. A molding apparatus of the character described including, a mold having vibratory sides, a vibrating base, a mold supporting pallet on said base, a guard releasably connected with said base and surrounding the upper portion of said mold with clearance to permit vibration of said sides, means engageable by said guard to locate and retain said mold on said pallet, and means for vibrating said base.

4. A molding apparatus of the character described including, a mold having vibratory sides, a core for said mold having a projection extending outside of said mold, a resilient connection between said mold and core, a bottom support for said mold, a guard resiliently connected with said support and surrounding the upper portion of said mold with clearance to permit vibration of said sides, said guard being engageable with said projection to locate and retain said mold and core on said pallet, and means for vertically vibrating said support.

5. A molding unit of the character described including, a mold, a core for the mold, a slack

connection permitting limited relative movement between the core and the mold, and releasable means for holding the core and mold against relative movement during the casting operation.

5 6. A molding unit of the character described including, a mold, a core for the mold, a slack connection permitting limited relative movement between the core and the mold, and yieldable means tending to urge said core and mold apart.

10 7. A mold having vibratory sides, a core for the mold having a projection extending outside of the mold, a yieldable connection between said projection and a part of the mold, a pallet for supporting said mold, a yieldable clamp for engaging said projection to locate and retain said core and mold on said pallet, and means for vibrating said core and mold.

15 8. A molding apparatus of the character described including a mold, a pallet for supporting said mold, a guard overlying said pallet and extending outside the upper portion of said mold, and means associated with said guard and bearing downwardly against the mold to retain it on said pallet.

20 9. A molding apparatus of the character described including a mold, a core structure for said mold, a support for said mold, a guard connected with said support and extending outside the upper portion of said mold and retaining means carried by said core structure and engaged by said guard to bear downwardly against the mold and retain it on said support.
